(57) **CLAIM**

The ornamental design for a wristband connector for mobile device, as shown and described.

DESCRIPTION

FIG. 1 is a front perspective view of a wristband connector for mobile device embodying the new design;

FIG. 2 is a front perspective view thereof, as shown in an alternate position.

FIG. 3 is a top plan view thereof;

FIG. 4 is a bottom plan view thereof; and

FIG. 5 is a right side elevational view thereof, the left side elevational view being a mirror image of the right side elevational view;

FIG. 6 is a rear elevational view thereof; and,

FIG. 7 is a front elevational view thereof.

The broken lines illustrating portions of the wristband connector for mobile device form no part of the claimed design.

1 Claim, 4 Drawing Sheets
